**WICK RAISING MECHANISM AND WICK CLIP
FOR INCANDESCENT BURNER**

Carl Bramming, Nashville, Tenn., assignor to Aladdin Industries, Incorporated, Chicago, Ill., a corporation of Illinois

Application January 17, 1952, Serial No. 266,898

4 Claims. (Cl. 67—60)

This invention relates to hydrocarbon burners, especially those in which fuels such as kerosene is burned, and more particularly to the provision of an improved wick raising mechanism and attachment means for releasably joining the wick to the raising mechanism.

In hydrocarbon burners, either stoves or lamps, employing a fuel feeding wick of tubular formation, the wick being nested between a pair of concentric tubular supporting members, and adapted to be raised and lowered in relation thereto, the difficulty of raising the wick in a uniform manner so as to present a uniformly planar edge at the desired combustion point must be met. It has been found advantageous to support the wick from diametrically oppositely positioned points, by some means designed to coat with a wick raising mechanism. An example of such a wick raising device and cooperating attachment means is disclosed in the patent to F. W. Spangler, No. 1,530,741, issued March 24, 1925. The present invention relates to a new attachment means and wick raising device which is an improvement over the one there shown.

Early wick-raising mechanisms were attached to or coated with the wick at only one point or along a line on the wall of the cylindrical wick and parallel to its axis. In use such means raised the wick so that it presented a high spot immediately above the point of engagement. The improved wick raising mechanism of the Spangler patent engages the wick at diametrically opposite points, but the engagement is of the pivotal type. In use the wick may become tipped, pivoting about the secondary axis determined by the support points, and present an entire side lifted higher than the other side.

In either of the above cases, uneven burning is encountered, and in hydrocarbon burning devices this results in yellow flame tongues and smoking. If the burner is used in conjunction with an incandescent mantle, the yellow tongues pass through the mantle and deposit large black carbon spots.

In accordance with the present invention, such tilting, with the accompanying flame tongues, smoking and blackening of the mantle, is prevented by providing wick raising mechanism and wick supporting means which position the wick evenly with respect to the burner head. To accomplish this end, the wick raising mechanism is constructed with a pair of arms having upper and lower edges situated in planes perpendicular to the longitudinal axis of the wick. The wick supporting means are clipped to the wick at diametrically opposite points, these means having a body or lug in which is defined a plurality of slots constituting a socket. In use the arms are firmly engaged in the slots, thereby providing a non-pivotal mounting, which makes tilting of the wick impossible.

It is therefore an object of the present invention to provide wick raising and attachment mechanism for use with cylindrical wicks employed in hydrocarbon burners, the mechanism being constructed so as to elevate and hold the wick evenly in position for burning.

A further object is to provide a wick raising mechanism for cooperation with a pinion supported in the basket of the burner, the wick raising mechanism being adapted to be stamped from relatively thin sheet metal, and requiring the use of only a small amount of metal.

A further object is to provide improved attachment means which may be associated with the wick, said attachment means constructed for engagement with the wick raising mechanism of the present invention.

A further object is to provide a wick engaging attach-

2

ment means having a novel means of association with the wick raising mechanism, whereby a smoother and more closely controlled movement of the wick may be obtained, in a semi-floating type of mounting, in a manner to prevent tilting of the wick to avoid uneven burning and undesirable flame tongues.

A further object is to provide a wick raising mechanism adapted to support the wick at two diametrically opposed points, the wick raising mechanism affording no interference with the transverse air tubes of a side draft burner.

Further objects and advantages of my invention will be apparent from a consideration of the following specification and appended claims in connection with accompanying drawings in which:

15 Fig. 1 is a view partially in elevation and partially in section of the wick supporting structure of a burner constructed according to my invention, some of the parts being omitted;

20 Fig. 2 is a view in section on the line 2—2 of Fig. 1; Fig. 3 is a view in section on the line 3—3 of Fig. 1;

25 Fig. 4 is a view in elevation of the wick raising mechanism, a wick clip, and wick, disassociated from the burner, and

30 Fig. 5 is a perspective view of the wick clip.

In the drawings, and particularly in Fig. 1, there is shown the wick supporting mechanism of a blue flame burner. This type of burner comprises a burner basket, not shown, in which the wick supporting mechanism is mounted. Above the burner basket there may be placed suitable mantle supporting means and an incandescent mantle, the entire structure cooperating to produce a high intensity light from a flame at the upper end of the wick.

As shown in the drawings, the wick 10, of cylindrical

35 formation embraces an inner wick tube 11 which extends downwardly in the burner and is pinched inwardly as at 12 where it is supported by the transverse air tube 13. The transverse air tube 13 is supported from the burner basket, not shown, and provides air to the inside of the

40 inner wick tube 11. A flame spreader 14, having its upper end perforated as at 15 may be inserted in the upper end of the inner wick tube 11 to function in the well-known manner, and may be supported therein by the tab 16 in the body of the inner wick tube 11.

45 The outer wick tube 17 is formed with an upper portion 18, of a diameter permitting a laterally supporting sliding fit with the wick 10 in operative position, and with a lower portion 19 of a large diameter and defining an annular chamber 20. The outer wick tube 17 is supported by a lower cylindrical frame 21, in turn mounted in the burner basket.

The wick 10 is formed with an upper cylindrical portion 22 and a lower bifurcated portion 23 permitting it to extend on either side of the transverse air tube 13, into the lower fuel tank. The wick attachment means 24

55 are secured to the wick 10, in its cylindrical portion 22, at opposite ends of a diameter perpendicular to the axis of the transverse tube 13, when the wick is in position. Each of these attachment means 24 is formed with a curved main body panel 24' having at each of its ends a deformable arm or gripper 25, adapted to be inserted through the body of the wick 10 and clinched as at 26, particularly as shown in Fig. 2, thereby holding the means 24 securely in position on the outside of the wick 10. The

60 main panel 24' is drawn into an outwardly extending stud 27, and defines a pair of slots 28 constituting a socket, as shown. The slots 28 extend vertically in the means 24, having their upper and lower ends situated in planes parallel to the plane of the upper end of the wick 10.

65 The wick supporting and raising mechanism 29 is formed with a substantially semicircular collar 30 which presents at its two ends the wick supporting arms 31, adapted to be received in the sockets formed by the slots 28 in the wick supporting means 24. In installing a new wick 10 in a device constructed according to this invention, it is found that the wick supporting arms 31 are easily engaged firmly in the slots 28, and that the assembly supports the wick 10 in a manner providing a sub-

70 stantially planar surface at the top of the burner head.

75 Since the arms 31 are firmly gripped in the sockets formed

by the slots 28, the wick is prevented from tipping as it is moved up and down.

The collar 30 is attached, at a point substantially off center as shown in Fig. 2, to a rack member 32, the two members being shown as formed of a single sheet of material. The rack 32 presents a plurality of teeth 33 adapted to be engaged by the teeth of the pinion 34 whereby the vertical position of the rack 32 and the wick 10 may be varied. The pinion 34 is supported on an axle 35 which carries a hand wheel 36 the assembly being mounted in the bracket 37 which is in turn attached to the supporting member 21. The guide channel 38 is formed by a portion of the bracket 37, and acts to guide the rack 32 and to hold it in position for movement by the pinion 34.

It will be appreciated that rotation of the hand wheel 36 will impart vertical movement to the rack 32 whereby the height of the wick 10 may be varied. The wick supporting means 24 cooperate with the wick supporting arms 31 as above described, and are also adapted to be used in connection with the wick supporting mechanism as shown in the above mentioned Spangler patent, by the engagement of the outwardly extending studs 27 with the apertures in the upper ends of the wick supporting arms there shown.

Having described my invention, what I claim as new and desire to protect by Letters Patent is:

1. In a burner, the combination comprising a vertically movable cylindrical wick, means forming a vertical rack guiding channel adjacent said wick, a rack movably positioned in said channel for upward removal therefrom, means including a pinion meshing with said rack for raising and lowering said rack, a generally semicylindrical wick supporting strip partly encircling said wick and rigidly connected to said rack adjacent its upper end so as not to interfere with upward removal of said rack from said channel, and a pair of wick mounting elements mounted on the outside of said wick at diametrically opposite points, each of said mounting elements including a vertical plate formed at opposite edges with inwardly extending prongs piercing said wick and clinched over to secure said plate to said wick, said plate having a pair of spaced vertical slots therein defining a central vertical strip portion therebetween formed outwardly into a U-shaped generally rectangular clip, said clips on said diametrically opposite mounting elements snugly and engageably receiving the opposite ends of said wick supporting strip and preventing tilting of said wick relative to said rack.

2. A mechanism for supporting and raising a cylindrical wick for a burner having a vertical rack guiding channel and a rack actuating pinion, comprising, in combina-

tion, a vertical rack movably receivable in the channel for upward removal therefrom and for meshing with the pinion, a generally semi-cylindrical wick supporting strip rigidly connected to said rack adjacent its upper end and receivable around the wick in partly encircling relation thereto, said strip providing for upward removal of said rack from the channel, a pair of wick mounting elements adapted to be secured to the outside of the wick at diametrically opposite points thereon, each of said elements comprising a vertical plate having means thereon for securing said plate to the wick, said plate having a pair of spaced vertical slots therein defining a central vertical strip portion therebetween formed outwardly into a U-shaped generally rectangular clip, said clips of said diametrically opposite mounting elements snugly and engageably receiving the opposite ends of said wick supporting strip to prevent tilting of the wick relative to the strip.

3. A wick mounting element for connecting a cylindrical wick to a wick raiser having a vertically movable rack-operated generally semi-cylindrical wick supporting strip, comprising a vertical plate, means for securing said plate to the outside of the wick, said plate having a pair of spaced vertical slots therein defining a central vertical strip portion therebetween formed outwardly into a U-shaped generally rectangular clip for snugly receiving one end of the wick supporting strip, two of said mounting elements being required at diametrically opposite points on the wick to connect the wick to both ends of the supporting strip.

4. A universal wick mounting element for connecting a cylindrical wick to a wick raiser, whether equipped with a generally semi-cylindrical wick supporting strip or, in lieu thereof, a pair of stud receiving arms, comprising a vertical plate formed at opposite edges with laterally extending prongs adapted to pierce the wick and be clinched over for securing said plate to the outside of the wick, said plate having a pair of spaced vertical slots therein defining a central vertical strip portion therebetween formed outwardly into a U-shaped generally rectangular clip adapted to receive one end of the wick supporting strip, said clip having a stud formed outwardly thereon adapted to receive one of the arms, two of said mounting elements being required at diametrically opposite points on the wick.
